UNITED STATES PATENT OFFICE.

MAT ROY THOMPSON, OF CHICAGO, ILLINOIS.

DISK FLANGE ATTACHMENT TO AUTOS AND TRAILERS.

1,352,561.

Specification of Letters Patent. Patented Sept. 14, 1920.

Application fil'd January 30, 1919. Serial No. 274,003.

To all whom it may concern:

Be it known that I, MAT ROY THOMPSON, a citizen of the United States, residing at Chicago, in the county of Cook, State of Illinois, have invented a new and useful Disk Flange Attachment to Autos and Trailers; and I do hereby declare the following to be a full, clear, and exact description of the invention, such as will enable others skilled in the art to which it appertains to make and use the same.

This invention relates to an improved disk flange attachment for automobiles and the like, and an object of the invention is to provide a device of this kind particularly applicable to wheeled vehicles, whereby they may travel safely along upon railway rails.

A further object of the invention is to provide means for raising and lowering the disk flange attachment, whereby the vehicle may travel the rails or a road bed. For instance, when traveling the rails, the disk flanges are lowered adjacent to the inner faces of the rail, in fact in contact with the inner edges of the tread or bull of the rails, thereby retaining the automobile wheels in engagement with the upper surfaces of the treads of the rails. When traveling a road bed, the disk flanges are raised.

A further object of the invention is the provision of means for yieldably mounting the disk flanges, so as to permit them to yield, or rise and fall, in order to pass over any obstruction in their path.

A further object of the invention is the provision of hanger means for the disk flanges, said means being constructed, to permit looseness of play, whereby the parts thereof may accommodate themselves to the vibrations of the body of the automobile.

A further object of the invention is the provision of latching means for maintaining the raising and lowering parts of the hanger in their lowered positions.

It is obvious that the outer faces of the disk flanges near their marginal edges play against the inner edges of the balls or treads of the rails, at points substantially directly under or slightly to the front or the rear of the main axles of the automobile, whereby said disks will play against the inner faces of the rims or tires of the automobile, or other vehicle, thereby maintaining the wheels in true positions on the rails.

In practical fields, the details of construc-

tion may necessitate alterations falling within the scope of what is claimed.

The invention comprises further features and combination of parts, as hereinafter set forth, shown in the drawings, and claimed. 60

In the drawings:

Fig. 1 is a view in side elevation of a conventional form of automobile, showing the disk flange attachment applied adjacent to the front and rear wheels. 65

Fig. 2 is a sectional view through the front axle of the automobile, showing the shaft carrying the disks in sections, and the hanger suspended from the chassis of the automobile and the axle thereof, and illustrating a 70 means for raising and lowering the parts of the hanger.

Fig. 3 is a rear view of the structure shown in Fig. 2, on line 3—3 thereof.

Fig. 4 is a detail sectional view of the front 75 axle and the clamp thereon, showing part of the hanger.

Fig. 5 is a detail sectional view through one of the disks, showing the ball bearings.

Referring more especially to the drawings 80 1 designates the frame or chassis of the automobile, and 2 and 3 the front and rear axles. Suitable clamps 4 and 5 corresponding to and fitting said axles are provided. Carried by and integral with the lower parts 85 of said clamps 4 and 5 are ball sockets 6, for the reception of the ball ends 7 of the guide rods or shafts 8 and 9. These guide rods or shafts 8 and 9 have their upper ends mounted in bearings of the cross pieces 10 of the 90 chassis or frame of the automobile. In fact the upper ends of the guide rods 8 and 9 are loosely mounted, so as to permit of sliding movements in the cross pieces, incident to the vibration of the body of the automobile. 95

Retaining plates 11 are secured at 12 to the ball sockets so as to retain the balls 7 in their sockets. The retaining plates 11 have openings 13, through which the guide rods or shafts 8 and 9 protrude. These openings 13 are large enough to permit of movements of the rods or shafts 8 and 9, as the balls 7 move slightly universally in their sockets, in order to accommodate themselves to the body of the automobile. It is obvious 100 that guide rods or shafts 8 extend upwardly and rearwardly, and the guide rods or shafts 9 extend upwardly and forwardly. However, should the front wheels of the automobile be sufficiently to the rear the guide rods 105 110

8, may, if practicable, be disposed in order to extend upwardly and forwardly. In the general construction of automobiles there is not sufficient frame forwardly of the front 5 wheels to permit the guide rods 8 to extend upwardly and forwardly. It is also obvious that the guide rods or shafts 8 and 9 are arranged in pairs, one pair forwardly and the other pair rearwardly disposed. Mounted 10 on each guide rod is a slide or block 14, to which the elongated spaced plates 15 are pivotally connected as at 16. The lower end portions of the plates 15 have vertical slots 17, for the reception of the headed pins 18 of the bearing blocks 19. The heads of the pins 18 retain the plates 15 in place. The upper faces of the bearing blocks 19 have pins 20. The adjacent portions of the upper ends of the plates 15 are integrally connected 20 by the cross bar or plate 21, downwardly from which a pin 22 extends axially toward the pin 20. A coil spring 23 is arranged between the plates 15, and its ends are retained in position by the pins 20 and 22. A 25 square axle or shaft 24 is mounted in bearings of the blocks 19, and its outer ends terminate in cylindrical portions 25, inclined upwardly and outwardly thereby providing trunnions for the disks 26, there being ball 30 bearings 27. Suitable nuts and washers 28 and 29 retain the disks on the trunnions. These disks act as wheel retainers, for retaining the tread surfaces of the tires of automobile wheels on the upper surfaces of the 35 balls of the rails 30, as shown clearly in Figs. 1 and 3, thereby enabling an automobile to travel safely along and upon the railway rails. It is obvious that by the provision of the slots 17 and the spring means 23, 40 either or both ends of the shaft 24 may yield vertically, thereby permitting the marginal edges of the disks 26 to ride over any obstruction in their path. It is also obvious that the axle is capable of vibrations with relation to the shaft 24 and vice versa, incident 45 to the yielding action of the tire. Furthermore, by means of the pivotal connections between the plates 15 and the bearing blocks and the slides 14, the parts of the hanger may 50 accommodate themselves to the lateral vibrations or strains of the axle. Pivoted at 31 to the inner face of each block or slide 14 is a latch dog 32, under tension of the spring 33. When the slide 14 is in its lowered position, the hook 34 of the dog or latch engages a rib 35 on the underface of the clamp of the wheel axle, thereby retaining the slide 14 in its lowered position. Mounted in bearings of the frame or chassis of the automobile fore and aft are shafts 36 and 37, on 55 which the drums 38 and 39 are mounted to rotate therewith. Attached to and wound about the drums are forward and rear cables 40 and 41, which are in turn connected at 42

to the latch dogs 32. Also rotatable with the 65 shafts 36 and 37 are worm wheels 43 and 44. Mounted in bearings 45 of the frame of the automobile and adjacent one side of said frame is a longitudinally extending shaft 46, provided with worms 47 and 48, which mesh 70 with the worm wheels 43 and 44. A vertical shaft 49 is mounted in bearings 50 of one side of the body of the automobile and its upper end is provided with a crank 51, and its lower end has beveled gear connections 52 75 and 53 with the shaft 46. It is obvious that when it is desired to permit the automobile to traverse the road bed instead of the rails, the chauffeur may operate the crank 51 which in turn will rotate the shaft 46, and impart 80 movement to the shafts 36 and 37 and their drums, thereby winding the cables 40 and 41 thereon. The pulling action of the cables will disengage the dogs from the flanges 35, and at the same time lift the slides on the 85 guide rods or shafts 8 and 9, consequently elevate the retaining disks 26, and leave the automobile wheels free to travel the road bed. A reverse movement of the crank 51 will unwind the cables and the slides 14 will 90 then lower through the medium of gravitation. When the dogs are disengaged from the flanges, they are limited in their movements by engaging the abutment pins 54.

The invention having been set forth, what 95 is claimed as new and useful is:—

1. In an attachment for automobiles, the combination with the automobile wheels adapted to ride balls of rails, of wheel retaining disks therefor, flexible hangers for 100 the disks, guides for the hangers, and means for raising and lowering the hangers on the guides, whereby the disks may be raised and lowered.

2. In an attachment for automobiles, the 105 combination with the automobile wheels adapted to ride balls of rails, of wheel retaining disks therefor, flexible hangers for the disks, guides for the hangers, and means for raising and lowering the hangers on the 110 guides, whereby the disks may be raised and lowered, and means for locking the hangers in their lowered position.

3. In an attachment for automobiles, the combination with the wheels thereof adapted 115 to ride the balls of railway rails, of retaining disks therefor, hangers, means for mounting the disks yieldably in the hangers, guides for the hangers, and means for raising and lowering the hangers on the guides, 120 whereby the disks may be raised or lowered.

4. In an attachment for automobiles, the combination with the wheels thereof, of retaining disks therefor to hold the wheels in true position upon the balls of railway rails, 125 flexible hangers, guides therefor, means for mounting the disks yieldably in the hangers, means for raising and lowering the hangers

simultaneously, whereby the retaining disks may be raised or lowered, and means for locking the hangers in their lowered position.

5. In an attachment for automobiles and other wheeled vehicles, the combination with the wheels thereof adapted to ride the balls of railway rails, of wheel retaining disks playing adjacent the inner surfaces of the 10 tires or rims of the wheels and the inner edges of the balls of the rails, for retaining the

wheels in true position on the balls of the rails, and means for suspending the retaining disks from the main axles of the automobile or other wheeled vehicle.
